(57) **CLAIM**

The ornamental design for a docking station for cellular telephone, as shown and described.

DESCRIPTION

FIG. 1 is a perspective view of a docking station for cellular telephone showing our new design;

FIG. 2 is a top plan view thereof shown without the environmental mobile telephone;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

In the drawings, the broken lines depict unclaimed environment.

The details shown in phantom are either representative of another device or do not constitute an integral part of the disclosure and the claimed design.

The ornamental design is for an article for use with a mobile telephone that may rest in a cradle adapted to support the mobile telephone, the cradle interfacing with a console having at least a handset, a display and a control pad.
